UNITED STATES PATENT OFFICE.

JOHN F. O'CONNOR, OF CHICAGO, ILLINOIS, ASSIGNOR TO WILLIAM H. MINER, OF CHAZY, NEW YORK.

YOKE FOR RAILROAD-CAR DRAFT-RIGGING.

1,198,753.

Specification of Letters Patent. Patented Sept. 19, 1916.

Application filed July 13, 1916. Serial No. 109,006.

To all whom it may concern:

Be it known that I, JOHN F. O'CONNOR, a citizen of the United States, residing at Chicago, in the county of Cook and State of Illinois, have invented a certain new and useful Improvement in Yokes for Railroad-Car Draft-Rigging, of which the following is a full, clear, concise, and exact description, reference being had to the accompanying drawings, forming a part of this specification.

My invention relates to improvements in yokes for railroad car draft rigging.

The object of my invention is to provide a yoke having a strong and readily detachable means for connecting the same to a draw-bar.

In the drawings forming a part of this specification, Figure 1 is a side elevation, partly in vertical longitudinal section, of a draft yoke embodying my invention. Fig. 2 is a horizontal section taken on line 2—2 of Fig. 1. Fig. 3 is a front end view of the yoke. Fig. 4 is a cross sectional view on line 4—4 of Fig. 1. Fig. 5 is a perspective view of the locking block. Fig. 6 is a perspective view of the locking key.

Referring to the drawings, the numeral 7 indicates a draw-bar having a butt 8 and the usual shoulders 9, 9 provided thereon. 10 indicates a yoke strap having an upper limb 11 provided at its forward end with the gib 12 to engage a shoulder upon the draw-bar, a lower limb 13, and a rear connecting member 14. At its forward end, the lower limb is provided with a transverse groove 15 that receives the lower section of the L-shaped key 16 which passes transversely of the yoke and extends at its ends through the slots 17, 17 provided in the yoke band 18, which is adapted to surround the draw-bar and yoke.

In the assembled position of the draw-bar and yoke, a block 19 is employed in effecting the connection between the same. The said block is provided at its forward end with an up-turned gib 20 which engages the lower shoulder 9 of the draw-bar, and at its rear end is provided with a down-turned gib 21 forming a shoulder 22 which engages against the rear face of the locking key 16.

It will be understood that the space 23 within the yoke is adapted to receive a draft gear. When the draft gear and the yoke

are in position upon a car, the draw-bar 55 may be easily connected to, or disconnected from the draft yoke.

In connecting the draw-bar to the yoke, the same is inserted rearwardly between the free ends of the yoke, and is then lifted upwardly until it assumes the position illustrated in Fig. 1 of the drawings, with the upper shoulder 9 of the draw bar in engagement against the gib 12 of the upper yoke limb. The locking block is then placed in 65 its position between the lower face of the draw-bar butt and the lower yoke limb, with the gib 20 thereof engaging the lower shoulder 9 of the draw-bar, and the yoke-band 18 being in position, the parts are 70 securely locked together by the insertion of the locking key 16, which in the ordinary construction of cars is sufficiently low to be inserted into, and removed from its position beneath the lower plane of the car's draft 75 members.

The reverse of the operation just described is employed in disconnecting the draw-bar from the yoke.

I claim:

1. In a draft rigging, in combination: a draw-bar; a yoke strap, a detachable band for surrounding the same, a block having upper and lower gibs, and a key, one limb of the yoke strap being provided with a gib 85 to engage the draw-bar, one gib of the locking block engaging another shoulder of the draw-bar, the other gib of the locking block engaging against the locking key, the key passing through the band and between the 90 locking block and the adjacent yoke limb.

2. In a draft rigging for railway cars, in combination: a draw-bar, a draft yoke, a band surrounding the draw-bar and yoke, a gib upon one limb of the yoke to engage the 95 draw-bar, a double-gibbed locking block and an L-shaped key, the key engaging one gib of the locking block and being interposed between the locking block and the adjacent yoke limb, the said yoke limb being 100 provided with a transverse groove to receive a portion of said key, and the band being slotted for the passage of the ends of the keys.

3. In a draft rigging for railway cars, a 105 draw-bar, a yoke, a band surrounding the draw-bar and yoke, a locking block and a key, the draw-bar being provided with op-

positely arranged shoulders, the yoke having a gib engaging one of said shoulders, the locking block having a gib engaging the other of said shoulders, the locking block being provided with a further gib, the locking key being engaged by said gib and passing through a slot in the adjacent yoke limb and through registering slots in the band.

In witness that I claim the foregoing I have hereunto subscribed my name this 6th 10 day of July, 1916.

JOHN F. O'CONNOR.
